UNITED STATES PATENT OFFICE.

FRANK DE CURTIS, OF MEDFORD, MASSACHUSETTS.

PERMUTATION LOCK.

Application filed October 23, 1925. Serial No. 64,344.

The chief object of the invention is to provide an improved and simplified permutation lock of compact form, adapted for use in locking the steering-wheel of a motor vehicle, as well as for other uses.

Another object is to provide a lock having registering means, adapted to guide the operator by a series of audible signals, during the operation of retracting the lock bolt.

10 The invention is embodied in the improvements which I will now proceed to describe and claim.

Of the accompanying drawings forming a part of this specification,—

15 Figure 1 is a top plan view of a motor-vehicle steering-wheel, and a lock therefor embodying the invention.

Figure 2 is a side view, portions of the wheel being broken away.

20 Figures 2^a and 2^b show in perspective, parts of the casing clamp hereinafter described.

Figure 3 is a section on line 3—3 of Figure 1.

25 Figure 4 is a section on line 4—4 of Figure 1, certain parts being omitted.

Figures 5, 6, 7 and 8 are front side views of the lock, the cover portion of the casing being removed, and the keeper shown 30 in section.

Figure 9 is an enlarged fragmentary section on line 9—9 of Figure 5.

Figure 10 is a perspective view of the bolt-carrying slide and the bolt.

35 Figure 11 is a perspective view of the locking-dog hereinafter described.

The same reference characters indicate the same parts in all of the figures.

The lock casing includes a back 12, a wall 40 or curb 13, integral with the back, and a front plate or cover 14, secured to the curb by screws 10, shown by dotted lines in Figure 2.

In this embodiment of the invention the 45 lock casing is rigidly secured, as hereinafter described, to spokes 15 of the usual steering-wheel, and the usual fixed tubular post or bearing 16, in which the steering-rod, carrying the steering-wheel, is journaled, is 50 provided with a keeper 17, having an arcuate series of bolt-receiving orifices 18, each of which is adapted to receive the locking bolt 20, which is movable in the casing, as hereinafter described, so that it may be projected from the casing and enter either orifice 18, according to the position to which

the steering-wheel is left when it is locked.

The casing is formed internally to guide the forked slide (Figure 10) to which the locking-bolt 20 is fixed. Said slide includes a neck portion 21, and parallel arms 22 and 23, and is in sliding contact with guides 24, formed by flattened portions of the curb or wall 13, the bolt being movable in a slot 25 (Figure 4) in the wall 13.

60 The arm 22 is provided with an elongated inwardly projecting ear 26, and the arm 23 with inwardly projecting studs 27, 27^a and 27^b, of which there may be any desired number, three being here shown.

65 The arm 22 is provided with an elongated inwardly projecting ear 26, and the arm 23 with inwardly projecting studs 27, 27^a and 27^b, of which there may be any desired number, three being here shown.

70 A screw-threaded spindle 28, having a thumb-knob 29 is supported by a sleeve 30 (Figure 4), having an internal screw-thread 31, engaging the spindle thread, and a thumb-knob 32, surrounding the spindle. 75 The sleeve 30 is journaled to rotate in the casing cover 14, and is provided with shoulders 33 (Figure 4) engaging the sides of the cover to prevent endwise movement of the sleeve.

80 The inner end of the spindle has a head 34, from which project in substantially opposite directions an ear-engaging tappet arm 35, and a stud-engaging tappet arm 36. A spring 37, connected with a fixed stud 38, 85 and with the arm 35, normally holds the arm 36 against a fixed stop 39 (Figure 5). A swinging-dog having arms 40 and 41 is pivoted on a fixed stud 42, on the cover 14, and is normally held by a spring 43 in the 90 position shown by Figure 5, its arm 40 engaging the slide arm 22, and locking the bolt against retraction from its projected position.

95 When the bolt is fully projected to lock the wheel 17, the parts are in the relative positions shown by Figure 5, the tappet arm 36 being held by the spring 37 against the stop 39, and the dog arm 40 being held by the spring 43, against the slide arm 22, and 100 confining the bolt in its projected position.

105 The studs on the slide arm 23 may have any desired relative arrangement, and their arrangement may differ in different locks, so that a different series of manipulations of the spindle will be required to unlock the wheel in each lock, the studs being arranged to be engaged successively by the tappet arm 36, and each engagement of said arm with a stud partly retracting the 110 bolt. At the commencement of the unlocking operation, the position of the spindle 28

is such that the stud 27 is in the path of the tappet arm 36, and in the position shown by dotted lines in Figure 4.

In unlocking the wheel, the operator first turns the spindle from the position shown by Figure 5, to that shown by Figure 6. This operation causes the tappet arm 36 to first engage the dog arm 41, and move the dog out of engagement with the slide arm 22, as shown by Figure 6, so that the bolt is free to be retracted. The tappet arm 36 then engages the stud 27, and retracts the bolt one step. The spindle is then released and is turned by the spring 37 until the arm 36 is arrested by the stop 39. The spindle is then longitudinally adjusted to the outer dotted line position shown by Figure 4, the path of the tappet arm 36, being thus changed so that the next turning of the spindle will cause said arm to engage the stud 27^a, and retract the bolt another step, as shown by Figure 7. The spindle is again released, and the tappet arm 36 is moved by the spring 37 against the stop 39. The spindle is again longitudinally adjusted to the inner dotted line position shown by Figure 4, to again change the path of the tappet arm 36, so that the next turning of the spindle will cause said arm to engage the stud 27^b, and complete the retraction of the bolt, as shown by Figure 8.

To project the bolt, the operator longitudinally adjusts the spindle to a position so locating the path of the tappet arm 36, that it will not engage either of the studs, and then turns the spindle backward, or in the direction of the arrow in Figure 8, thus causing the tappet arm 35 to engage the ear 26 on the slide arm 22, and project the bolt, the said ear being elongated, so that it will be in the path of the arm 35, in any longitudinal adjustment of the spindle.

The number of turns of the knob 32 and sleeve 30 required to longitudinally adjust the spindle 28 to each of the positions above described, is indicated by registering means embodied in a click spring 45 (Figures 1, 2 and 9), projecting from the casing, and a stud 46 fixed to the sleeve 30, and involved thereby, the stud being arranged to flex the spring 45 in passing across the same. When the stud releases the spring, the latter snaps audibly back to its normal position. The operator is informed by the number of snaps, or audible signals, when the spindle has been adjusted to bring the tappet arm 36 to either of its operative positions. The click spring is preferably fixed to a bushing 47, secured in an orifice 48 in the casing cover 14, as shown by Figure 9.

To frictionally oppose loose downward movement of the bolt, I provide frictional means including a shoe 49 (Figure 5), pressed by a spring 50, against the slide

arm 23, said shoe and spring being contained in a socket on one side of the casing wall 13.

The spindle 28 is guided in its longitudinal movements by a fixed steady-pin 52, (Figures 4 and 5), attached to the casing 70 back 12, and projecting into a longitudinal socket in the spindle.

To permit the securing of the lock casing to the spokes 15 of the steering-wheel, I provide the casing with a clamp including 75 means for engaging two adjacent spokes, as indicated by Figures 1, 2 and 3, the arrangement being such that the casing projects downward from the wheel at the hub portion thereof.

The clamp is preferably carried by the casing cover 14, said cover being provided with an extension 14^a, projecting between the spokes 15. On said extension is formed an integral clamping head 54, arranged to bear 85 on the upper sides of the spokes and provided with spoke-receiving recesses 55 (Figure 2^a). 56 designates an independent clamping plate, formed to bear on the under sides of the spokes below the head 54. The arms 54 and plate 56 are connected by clamping screws 57 (Figures 2 and 3). The head 54, plate 56, and screws 57 constitute a clamp adapted to engage an ordinary steering-wheel, without change or adaptation of the latter.

The screws 57 may be originally formed with extensions 57^a, as shown by dotted lines in Figures 2 and 3, projecting above the clamping heads of the screws and adapted to be turned to drive the screws and then cut off close to the clamping heads, so that the screws cannot subsequently be engaged by a removing tool, the casing being therefore inseparably secured to the wheel.

The keeper 17 is segmental and its inner side is formed to bear on one side of the post 16. The keeper is provided with a post-engaging clamp including a shoe 59, formed to bear on the opposite side of the post, and clamping screws 60, securing the shoe to the keeper. The shoe may be additionally secured to the post by a set screw 61.

The keeper and its clamp thus constituted are adapted to be engaged with an ordinary 115 post 16, without change or adaptation of the latter. The clamping screws 60 may be provided with extensions 60^a, adapted for use in driving the screws, and adapted to be cut off to prevent the removal of the 120 screws.

I claim:

1. A permutation lock comprising a casing, a slide movable in a predetermined path in the casing, and composed of spaced 125 apart arms and a connecting neck, one of said arms having a plurality of studs, and the other an elongated ear, a bolt fixed to said neck and movable in a slot in the casing, an internally threaded sleeve journaled 130

in a bearing on the casing, an externally threaded spindle engaged with said sleeve, and having oppositely projecting tappet arms, one adapted to cooperate with said 5 studs in retracting the bolt, and the other adapted to engage said elongated ear and project the bolt, said spindle being longitudinally adjustable by the sleeve, and a stop within the casing against which one of 10 said tappet arms is yieldingly held, the arrangement being such that one of the tappet arms is adapted to engage said studs successively, to retract the bolt step-by-step when the spindle is turned in one direction, 15 the other tappet arm being engageable with said elongated ear by a reverse turning of the spindle, to project the bolt, the lock comprising also registering means, including a click spring on said casing, and a stud 20 on said sleeve adapted to cooperate with said spring in giving an audible signal.

2. A permutation lock comprising a casing, a slide movable in a predetermined path in the casing, and composed of spaced apart arms and a connecting neck, one of 25 said arms having a plurality of studs, and the other an elongated ear, a bolt fixed to said neck and movable in a slot in the casing, an internally threaded sleeve journaled 30 in a bearing on the casing, an externally threaded spindle engaged with said sleeve, and having oppositely projecting tappet arms, one adapted to cooperate with said studs in retracting the bolt, and the other 35 adapted to engage said elongated ear and project the bolt, said spindle being longitudinally adjustable by the sleeve, and a stop within the casing against which one of said tappet arms is yieldingly held, the arrangement being such that one of the tappet arms is adapted to engage said studs successively, to retract the bolt step-by-step, by a rotation of the spindle in one direction, and to displace the 40 dog when moved to engage the first stud, the other tappet arm being engageable with said ear by a reverse rotation of the spindle, to project the bolt and permit the engagement of the dog with the bolt.

when the spindle is turned in one direction, the other tappet arm being engageable with said elongated ear by a reverse turning of the spindle, to project the bolt, the said casing being provided with frictional means engaging said slide, to prevent loose movement of the slide and bolt.

3. A permutation lock comprising a casing, a slide movable in a predetermined path in the casing, and composed of spaced apart arms and a connecting neck, one of said arms having a plurality of studs, and the other an elongated ear, a bolt fixed to said neck and movable in a slot in the casing, a two-armed dog pivoted in the casing and normally held with one of its arms engaging an arm of said slide to hold the bolt projected, an internally threaded sleeve journaled to rotate in a bearing on the casing, an externally threaded spindle engaged with said sleeve, and having oppositely projecting tappet arms, one adapted to cooperate with said studs in retracting the bolt, and the other adapted to engage said elongated ear and project the bolt, said spindle being longitudinally adjustable by the sleeve, and a stop within the casing against which one of said tappet arms is yieldingly held, the arrangement being such that one of the tappet arms is adapted to engage said studs successively, to retract the bolt step-by-step, by a rotation of the spindle in one direction, and to displace the dog when moved to engage the first stud, the other tappet arm being engageable with said ear by a reverse rotation of the spindle, to project the bolt and permit the engagement of the dog with the bolt.

In testimony whereof I have affixed my signature.

FRANK DE CURTIS.
